FOREIGN PATENT DOCUMENTS

EP 2913274 A1 9/2015

Primary Examiner — John Windmuller*Assistant Examiner* — Steven J Czyz(74) *Attorney, Agent, or Firm* — Westerman, Hattori, Daniels & Adrian, LLP(57) **CLAIM**

The ornamental design for a counter display, as shown and described.

DESCRIPTION

FIG. 1 is a perspective view of a counter display;
FIG. 2 is a front view of the counter display;
FIG. 3 is a back view of the counter display;
FIG. 4 is a left side view of the counter display;
FIG. 5 is a right side view of the counter display;
FIG. 6 is a top view of the counter display;
FIG. 7 is a bottom view of the counter display; and,
FIG. 8 is an environment view of the counter display.
The broken lines in the drawings illustrate portions of the counter display that forms no part of the claimed design.
